UNITED STATES PATENT OFFICE.

SAMUEL R. KEIM, OF JOHNSTOWN, PENNSYLVANIA.

METALLIC RAILWAY-TIE.

No. 902,414.

Specification of Letters Patent. Patented Oct. 27, 1908.

Application filed May 29, 1908. Serial No. 435,688.

To all whom it may concern:

Be it known that I, SAMUEL R. KEIM, a citizen of the United States, residing at Johnstown, in the county of Cambria and State of Pennsylvania, have invented new and useful Improvements in Metallic Railway-Ties, of which the following is a specification.

My present invention relates to improvements in railway cross-ties of the type composed essentially of metal to serve as a substitute for the usual wooden tie, and it has for its object primarily to provide a simple, relatively inexpensive and improved tie of this character which may be readily and cheaply constructed preferably of rolled metal which possesses the requisite strength and cheapness, and which is provided with devices which in practice serve to effectually lock the rails thereto, the rail locking devices being such that the proper gage of the rails is rigidly maintained by means of a central locking member which extends between them, and any loosening tendency of the rails resulting from wear or other causes may be taken up, or compensated for by means of outer adjustable locking members.

Another object of the invention is to provide a railway tie of this character embodying a central locking member which spans the space between the two rails and is provided with means for drawing it downwardly to lock the rails and a pair of outer locking members which are provided with means for drawing them in a direction both downwardly and inwardly so as to fasten the rail down and also to lock it firmly in coöperative relation with the central locking member.

Further objects of the invention are to provide means for yieldingly supporting the rails upon the tie whereby vibrations or noise caused by passing trains is minimized and also to improve the general construction of the tie whereby the same is closed at the top so as to not render it dangerous to the employees, and also to provide such a construction wherein the parts may be readily removed or adjusted as occasion may require.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is a perspective view of a section of a railway equipped with ties constructed in accordance with my present invention, the outer locking member of one of the ties being shown removed; Fig. 2 represents an end elevation of a section of the railway, a portion of the foremost tie being broken away so as to show the means for supporting and locking one of the rails in proper position; Fig. 3 is an enlarged detail view of one end of a tie, the rail and tie being shown in plan; and Fig. 4 represents a transverse section of the tie on the line 4—4 of Fig. 2.

Similar parts are designated by the same reference characters in the several views.

Railway ties constructed in accordance with my present invention are capable of use generally in connection with railways of various kinds, and it will be understood, of course, that in applying the ties to railways of different gages, the relative proportion of the parts will be correspondingly varied. It will also be understood that I have shown in the drawing one specific embodiment of the invention, and that the invention is not necessarily so limited, as certain changes in the specific construction of the parts or the relative arrangement thereof may be made in order that the invention may be applied to the best advantage in each particular case.

In the present instance, the tie comprises a main or body member 1 which is preferably formed of sheet metal rolled into a channel form, the intermediate portion of the channel being adapted to rest flatwise upon the bed of the track, and the longitudinal flanges 2 and 3 extend upwardly, the main or body section just described being of such a length as to extend between the rails and to project a suitable distance at the opposite sides thereof.

In order to yieldingly support the rails upon the tie so as to ease or absorb vibration and thus minimize wear and noise caused by the motion of the rolling stock over the rails, a supporting block 4 is mounted between the longitudinal flanges of the base member, this block being composed of wood or other appropriate material and is of such a height that its upper edge lies in a plane sufficiently above the tops of the longitudinal flanges, these flanges being arranged to engage the opposite sides of the block to prevent shifting thereof in a direction longitudinally of the rail. The rails are locked to the tie and

are rigidly maintained at the proper gage by means of a central locking member 5 and a pair of coöperating outer locking members 6 and 7. These locking members are also 5 formed preferably of sheet metal, such as steel, rolled into channel form, these members being arranged in reverse relation to the channel-shaped base member, and the width between the longitudinal flanges 10 thereof is such as to enable these members to closely fit between the corresponding flanges of the base member. These members may be cheaply made by shearing or otherwise severing sections from a strip of channel-shaped metal, the central locking member having its vertical flanges undercut or cut away at a point inwardly from the end of the member so as to form a pair of outwardly projecting or overhanging locking 15 jaws 8 and 9, and this locking member is of such a length that when its locking jaws engage the base flanges of the two rails, the latter will be positively spaced at the proper gage, and this central locking member is 20 drawn into locking engagement with the two rails by means of a suitable number of wedges, a pair of wedges 10 and 11 being shown in the present instance which are arranged toward the respective ends of the 25 central locking member, these wedges each passing through registering openings 12 and 13 formed respectively in the longitudinal flanges of the base and locking members so that as the wedges are driven in, they will 30 draw the member downwardly into firm engagement with the rail and in locked relation to the base. In order to prevent loosening of these wedges, a cotter pin or other locking device 14 is preferably passed 35 through an appropriate aperture formed in the smaller end of the wedge.

The two outer locking members are substantially duplicates, each having the inner ends of its vertical flanges undercut to form 40 an overhanging jaw 15 which is adapted to engage over the outer side of the base flange of the rail. These outer locking members are drawn into engagement with the respective rails by a diagonal movement in a direction both downwardly and inwardly, and any appropriate devices may be employed for accomplishing this result. In the present instance, pairs of diagonally-arranged apertures or slots 16 are formed in the opposite flanges of each outer locking member 45 and are arranged to register with correspondingly inclined apertures or slots 17 formed in the flanges of the base member. The wedges 18 are adapted to enter these 50 registering apertures and, when driven into position, will firmly draw the respective locking member into engagement with the rail in a direction that will operate to draw the rail downwardly against the supporting 55 block and also clamp the same against the

corresponding end of the central locking member so that lateral shifting of the rail either vertically or horizontally is positively prevented.

It will be understood, of course, that while I have shown a certain number of locking wedges for drawing the respective locking members into engagement with the rail, the invention is not necessarily limited in this respect, as certain of these wedges may be omitted, or, additional ones employed as may be found desirable or necessary. The rail supporting block 4, it will be observed, is held from shifting longitudinally of the tie by means of the wedges 10 and 18 between which it is interposed, although should this block become worn, it may be readily removed and another substituted by first unlocking the corresponding outer locking member and removing it, it being unnecessary to even disturb the rail in removing and replacing these supporting blocks. By employing wedges for drawing the respective locking members into engagement with the rail, it will be obvious that any wear liable to occur by reason of the passage of the trains over the rails may be readily taken up or compensated for by merely driving in the wedges further and appropriately fitting the cotter pin to prevent their working loose.

Railway ties constructed in accordance with my present invention are composed of a few parts which are relatively simple in construction and which may be manufactured cheaply from rolled metal, metal of channel form being generally preferable because of its stiffness which renders the tie rigid longitudinally, and moreover, by constructing the base member and the locking members both of channel form arranged in reverse relation and fitting one within the other, the locking members serve not only to retain the rail in coöperative relation with the tie, but they also close the upper side of the tie so that no openings are formed in which the foot of an employee might catch. The use of rolled metal also renders the liability of breakage or fracture of the tie negligible. The improved manner of mounting the locking members in the channel-shaped base member also enables these members to be readily applied during the construction of the railway, and one or both of the outer locking members may be quickly and easily adjusted to compensate for wear, or, they may be readily removed and replaced in substituting a new rail supporting block for a worn one.

I claim as my invention:

1. A railway cross tie comprising a base member of channel form, and a rail locking and spacing member of channel form fitted into the base member to close the opening between its flanges and provided with means

for locking said member in coöperative relation to both rails and base member.

2. A railway cross tie comprising a base member of channel form having its longitudinal flanges upturned, a set of rail locking members of channel form arranged in inverted relation to the base member and having their flanges arranged to coöperate with those of the base member, and means co-
operating with the rail locking members to draw them into coöperative relation with the rails and the base member.

3. A metallic railway tie comprising a base member, a central locking member of a length sufficient to span the space between the rails and to engage the base flanges thereof, a pair of outer rail locking members mounted on the base member and adapted to engage with the outer sides of the rails, and means for securing the locking members in engagement with the rails.

4. A railway cross tie comprising a base member, a central locking member adapted to span the space between the rails and having jaws at its ends to coöperate with the base flanges of the respective rails, means for drawing said central locking member downwardly into engagement with the rails, a pair of outer locking members having jaws to engage the base flanges of the respective rails at their outer sides, and means for drawing the outer locking members into engagement with the respective rails by a diagonal movement both downwardly and inwardly.

5. A railway cross tie comprising a base member of channel form, a central locking member also of channel form and arranged in inverted relation within the vertical flanges of the base member, said central locking member being provided with rail engag-

ing jaws at its opposite ends, wedges coöperating with the flanges of the base member and central locking member respectively for drawing the latter downwardly into locking engagement with the rails, a pair of outer locking members also of channel form having their flanges engaging within the flanges of the base member, the flanges of the outer locking members and the flanges of the base member being provided with diagonally arranged wedge openings; and wedges arranged to coöperate with said openings to draw the outer locking members into engagement with the respective rails by diagonal movements both inwardly and downwardly.

6. A railway cross tie comprising a base member, a central locking member fitting the base member and provided with transverse wedges coöperating with its ends to draw it into engagement with the respective rails, a pair of outer rail locking members having jaws to engage the outer sides of the respective rails, removable wedges coöperating with the base member and the respective outer locking members for drawing the latter into engagement with the respective rails, and a yielding rail supporting block resting upon the base member and having its ends arranged to engage the transverse wedges of the locking members to prevent displacement of the block in either direction longitudinally of the tie.

In testimony whereof I have hereunto set my hand in presence of two subscribing witnesses.
